SIGN DEVICE

Harry W. Fuerst, Los Angeles, Calif., assignor of
one-half to C. Bland Jamison and one-half to
Miller Allen, Los Angeles, Calif.

Application August 6, 1949, Serial No. 108,899

2 Claims. (Cl. 40—34)

1

This invention has to do with sign devices and has as an object the provision of a sign capable of attracting and holding the attention of an observer.

It is also an object to provide a device of this character which includes, in combination with a loud speaker, a sign in which the words are progressively displayed and rendered visible by fluorescence.

Another object is to provide a portable dais incorporating my novel sign device.

More particularly, it is an object to provide a sign device wherein a wall or disk is mounted to rotate partly in one viewing compartment and partly in a separate viewing compartment, and wherein the lighting system and the materials of which the sign is painted fluorescence in the light in only one compartment, while the letters of the sign remain latent or substantially invisible in the light in the other compartment.

Other objects will appear hereinafter.

Without intending to limit the invention, except as may be indicated by the appended claims, I shall now, for the purpose of explaining my invention, describe preferred embodiments, for which purpose I shall refer to the accompanying drawings, wherein:

Fig. 1 is a front elevation with a part of the disk broken away for illustrative purposes;

Fig. 2 is a section taken on line 2—2 of Fig. 1;

Fig. 3 is a section taken on line 3—3 of Fig. 1; and

Fig. 4 is a side view partly in elevation and partly in section, showing another adaptation of the invention.

Referring now to the drawings, I show at 5 a box-like casing having front end extensions 5a projecting beyond and framing the front end wall 6.

It is my preference to make the front end wall in such manner as to pass sound from a loud speaker 7 forming part of a sound reproducing unit 8 within the casing. For this purpose, I show an opening 9 through the wall, although the wall could be made of foraminated material.

A division wall 10 divides the area framed by the extensions 5a into two compartments 15 and 16, and a disk 18 is mounted to rotate between the end wall 6 and the inner edge of the division wall so that at all times one-half of the disk is visible in compartment 15, while the other half of the disk is visible in compartment 16.

Generally speaking, I create an unusual attention attracting and holding feature in con-

2

nection with the rotating disk by using a combination of paints and light sources wherein indicia displayed in paint capable of absorbing light of particular wave lengths fluoresces in light having such wave lengths but is substantially invisible in light of other wave lengths.

For instance, it is my preference to coat the disk 18 with fluorescent paint having a yellow pigment and, upon said coating I paint indicia 20 in a transparent color and mount a black fluorescent light 22 in compartment 15 so that, in that compartment, the disk appears in one color while the indicia appears in another color, while, in the lower compartment 16, in which I may mount a white fluorescent light 23, the disk is illuminated but the indicia 20 does not fluoresce. However, I prefer also to paint a second indicia 24 in a non-fluorescent type of paint, which becomes outstandingly visible in the white fluorescent light in compartment 16, although latent or not clearly visible in the light in upper compartment 15.

The disk 18 is rotated counter-clockwise by a motor M in the casing through the medium of a shaft 25 upon which the disk is secured.

From the foregoing it will be apparent that my sign is capable of attracting and holding attention since it is an animated type of sign and is one which possesses that degree of incongruity to cause an observer to wonder how it works. Moreover, in the preferred form of my device, I use the sound producing unit which adds the feature of sound which emanates through the framed area occupied by the sign.

For instance, I find that my sign is peculiarly useful in enabling a speaker to hold the attention of an audience, and in Fig. 4 I show an adaptation of the invention in the form of a portable dais generally denoted 40. The dais consists of a casing having a sloping top wall 41, side walls 42, rear wall 43, front wall 44 and a bottom wall (not shown). The side, top and bottom walls have extensions 50 like the extensions 5a previously described to frame the front end wall 44 in the manner previously described to provide, together with the partition wall 10a, a pair of compartments 15a, 16a within which a disk 18a is mounted to rotate in the manner hereinbefore described. The sign indicia on the disk and the lights 22a, 23a correspond to the lights 22 and 23 and the disk 18 previously described.

A hood 51 may be provided for a reading light 52, and an adjustable microphone 55 is mounted on the top wall 41 being connected into the sound producing unit 8a through cable 56.

Wires 60 connect the speaker and motor of the device of Figures 1-3, and similar wires (not shown) connect the corresponding elements of the device of Fig. 4 to such sources (not shown).

I claim:

1. In a sign device having a pair of juxtaposed viewing compartments, a wheel mounted to rotate partly in the first and partly in the second of said compartments, with its front surface visible from the exterior of said compartments, sign indicia disposed circumferentially of the front surface of said wheel, said indicia being formed of material capable of fluorescing in light of a given wave length, and means for exposing said indicia to light of said wave length in only 15 one of said compartments.

2. In a sign device having a pair of juxtaposed viewing compartments, a wheel mounted to rotate partly in the first and partly in the second of said compartments, with its front surface visible 20 from the exterior of said compartments, means for rotating said wheel; a coating of fluorescent

paint on said wheel, sign indicia painted on said coating, said sign indicia being formed of transparent paint of a color differing from the color of said coating, a light source in one of the compartments capable of producing light of a wave length absorbable by said coating of fluorescent paint and also of a wave length capable of fluorescing said sign indicia.

HARRY W. FUERST.
